UNITED STATES PATENT OFFICE

151,623

DESIGN FOR A HOUSEHOLD DUSTER

David Heller, New York, N. Y.

Application December 10, 1946, Serial No. 135,383

Term of patent 14 years

(Cl. D9—2)

To all whom it may concern:

Be it known that David Heller, a citizen of the United States of America and resident of the city and State of New York, has invented a new, original, and ornamental Design for a Household Duster, of which the following is a specification, reference being had to the accompanying drawing, forming part thereof, in which

Fig. 1 is a perspective view of a household duster, embodying my new design, and showing the same in one of its positions for dusting use;

Fig. 2 is a view similar to Fig. 1, but illustrating the household duster in another of its positions for use; and

Fig. 3 is a perspective view thereof showing the duster in its lowered position for storage.

I claim:

The ornamental design for a household duster, substantially as shown.

DAVID HELLER.
